US00D416281S

United States Patent [19]

[19]

[11] Patent Number: Des. 416,281

[45] **Date of Patent:** ** **Nov. 9, 1999**

[54] TYPE FONT

Primary Examiner—Louis S. Zarfas
Assistant Examiner—G. Andoll

[75] Inventor: **Zuzana Licko**, Berkeley, Calif.

[73] Assignee: **Emigre, Inc.**, Sacramento, Calif.

[**] Term: 14 Years

[21] Appl. No.: 29/093,601

[22] Filed: Sep. 15, 1998

[51] LOC (6) Cl. 18-03

[52] U.S. Cl. D18/24
